UNITED STATES PATENT OFFICE

2,270,034

WASTE METAL CATCHER FOR TYPE
CASTING MACHINES

George L. Curle, Minneapolis, Minn.

Application May 12, 1941, Serial No. 393,030

12 Claims. (Cl. 199—59)

My present invention relates to improvements in waste metal catchers for use in connection with type casting machines. While this invention is intended for general use, it is especially well adapted for use in connection with waste metal spouting systems of the type disclosed and broadly claimed in my two United States Letters Patents No. 1,875,565 issued September 6, 1932, and No. 2,186,801 issued January 9, 1940.

The object of these spouting systems is to receive and collect waste metal cut from type slugs or bars by the back knife, waste metal spill from the mold wheel, shavings removed from type slugs by the knife wiper and waste metal and dust from a type slug sawing attachment, provided the type casting machine is equipped with the same.

These catchers are provided and arranged to receive waste metal discharged from spouting systems at the terminals thereof and to receive rejected type slugs thrown by hand by the operator of the machine.

More specifically stated, this invention is in the nature of an improvement or a refinement on the waste metal catchers shown in the above identified patents wherein the waste metal catchers are removably mounted on under-slung brackets detachably secured to the machines. These brackets are objectionable for the reason that they materially interfere with the care of the machine and the floor thereunder, as well as certain adjustments of the machine that have to be made from time to time, and said brackets often have to be removed from the machine in order to make the required adjustments.

One of the objects of this invention is to removably suspend the receptacle of the waste metal catcher from an overhead support or cover, whereby when said receptacle is removed therefrom, the space below said support or cover is unobstructed.

Another object of this invention is to provide means whereby the receptacle of a waste metal catcher will freely slide from an overhead support or cover when removing said receptacle therefrom to empty the load of waste metal therein.

A further object of the invention is to provide an overhead support or cover for the receptacle of a waste metal catcher that will direct waste metal from a spouting system or thrown by hand without spill or over-shot.

Still another object of this invention is to provide an overhead support or cover for the receptacle of a waste metal catcher having a novel

apron for directing waste metal from a slug sawing attachment into the receptacle.

These and other objects of the invention will be apparent from the following description and accompanying drawings.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a fragmentary view in left-hand side elevation of a type casting machine having the invention mounted thereon;

Fig. 2 is a front elevation of the parts shown in Fig. 1;

Fig. 3 is a view principally in plan of the parts shown in Fig. 1, with some parts sectioned on the line 3—3 of Fig. 1;

Fig. 4 is a fragmentary view partly in front elevation and partly in section taken substantially on the line 4—4 of Fig. 3;

Fig. 5 is a view in vertical section taken on the line 5—5 of Fig. 4;

Figs. 6, 7 and 8 are fragmentary detail views partly in elevation and partly in section taken on the lines 6—6, 7—7, and 8—8 of Fig. 3, respectively; and

Fig. 9 is a fragmentary detail view partly in plan and partly in horizontal section taken on the line 9—9 of Fig. 3.

Of the parts of the type casting machine fragmentarily illustrated for the purpose of showing the invention in working position, it is important to note the central supporting pedestal 10, the horizontal left-hand member or angle bar 11 of the main frame having on its front end a bearing 12, the upright standard 13 on the member 11 that forms a part of the main frame, the transverse shaft 14 journaled at one end in the bearing 12, the left-hand leg 15 of the melting pot, not shown, pivoted on the shaft 14, the left-hand leg 16 of the vise frame, not shown, pivoted on the shaft 14, the left-hand justification lever 17 and its rod 18 and operating spring 19 and certain parts of the quading and centering mechanism indicated as an entirety by the numeral 20.

Mounted on the type casting machine and fragmentarily illustrated is a spouting system, and of the parts thereof shown it is important to note the discharge end portion of a spout 21 that collects and conveys waste metal taken from slugs by the back knife, and the delivery end portion of

a spout 22 that collects and conveys waste metal spill from the mold wheel and shavings removed by the knife wiper. The spout 21 is provided with an auxiliary extension 23 having a depending lip 24. The numeral 25 indicates the discharge spout, fragmentarily illustrated, of a slug sawing attachment, not shown. The discharge spout 25 extends transversely in front of the leg 16 and is secured thereto.

Referring now in detail to the improved metal catcher, the numeral 26 indicates a scoop-like receptacle having an open top. In the front member of the receptacle 26 is a hand hole 27 and an intermediate transverse handle 28 is secured at its ends to the sides of said receptacle at the top thereof. The upper edge portions of the side members of the receptacle 26 are turned outwardly into horizontal positions to afford at each side of the receptacle 26 a longitudinal flange or rail 29.

The receptacle 26 is removably suspended from the type casting machine by means of an overhead support or cover 30. This cover 30 is located on the left-hand side of the type casting machine and extends from the front toward the rear thereof. The major portion of the cover 30 is outwardly of and below the frame member 11. The left-hand side member of the cover 30, at its rear end portion and top thereof, is inset at 31 to receive the front end portion of the frame 11 and its bearing 12, see Fig. 6. The cover 30 is detachably secured to the frame member 11 by bolts 32, and its top member is downwardly and outwardly inclined from the upper face of said member and affords clearance for the left-hand justification lever 17 which works thereabove.

The receptacle 26 is removably supported from the cover 30 by means of rollers 33 on which the tracks 29 rest. These rollers 33 are journaled on the side members of the cover 30 at the inner faces thereof in longitudinally spaced arrangement. The rollers 33 are located at the lower edge portions of the side members of the cover 30 and the front member of said cover, at its lower edge portion, is cut away at 34 to permit the receptacle to enter the cover 30 by sliding its rails 29 on the rollers 33, see Fig. 6.

On the front member of the cover 30 are outwardly extended flanges 35 arranged to engage the front ends of the side members of the cover 30 as stops to limit the movement of the receptacle 26 under said cover and position its front member in the plane of the front member of the cover 30.

On the right-hand side of the cover 30 at the front thereof is a hopper 36. The auxiliary spout 23 and its lip 24 are arranged to discharge waste metal received from the spout 21 into the hopper 36 at the rear end thereof and the spout 22 is also arranged to discharge waste metal into the hopper 36 at the rear end thereof.

It is well known that the legs of the vise frame, which are pivoted on the shaft 14, swing forwardly when said frame is opened and hence the discharge spout 25 of the slug-sawing attachment which is secured to the vise frame leg 16 moves therewith. In view of this movement of the spout 25 relative to the hopper 36, said spout cannot be arranged to extend over said hopper and discharge waste metal directly therein.

To carry waste metal from the spout 25 and discharge the same into the hopper 36, I provide a novel apron 37. This apron 37 is connected at its lower end by a hinge 38 to the upper

edge of the right-hand side of the hopper 36. Said apron 37 is upwardly and outwardly inclined away from the waste metal catcher and bears its upper end against the leg 16 and holds said apron under the spout 25. In the upper end portion of the apron 37 is an intermediate cam surface 39 that normally extends in front of the legs 16. When the vise frame is opened, its leg 16 engages the cam surface 39 and moves the apron out of the path of movement of said leg. Gravity holds the apron 37 against the leg 16 and returns said apron to operative position when the vise frame is closed. On the front edge of the apron 37 is a perpendicular flange 40 that extends into the hopper 36 and overlaps the front member thereof.

Waste metal discharged into the hopper 36 from the spouts 21 and 23, 22 and 25 is precipitated through said hopper and the cover 30 and into the receptacle 26.

The left-side member of the hopper 36 is extended above the front member of said hopper to afford a deflecting flange 41 for intercepting discarded slugs thrown by the operator over the hopper and directing the same therein.

By reference to Fig. 1 it will be noted that the quadding and centering mechanism 20 is substantially entirely rearwardly of the receptacle 26 and the cover 30 and the major portion thereof is below said cover.

When the receptacle 26 is removed from the cover 30, free access may be had to the quadding and centering mechanism 20 and other parts of the machine normally covered or obstructed by said receptacle. The entire space between the cover 30 and the floor x , when the receptacle 26 is removed, is unobstructed.

As the improved waste metal catcher is substantially entirely to the left of the type casting machine, it is not in the way of the operator of the machine or does not interfere with access to the machine from the front thereof.

From what has been said, it will be understood that the waste metal catcher described is capable of modifications as to details of construction and arrangement within the scope of the invention herein disclosed and claimed.

What I claim is:

1. A waste metal catcher for a type casting machine comprising a receptacle, a cover for the receptacle applicable to said machine in an elevated position, said receptacle being removably suspended from and below its cover, and means for directing waste metal from the machine through the cover and into the receptacle.

2. A waste metal catcher for a type casting machine comprising a receptacle, a cover for the receptacle applicable to said machine in an elevated position and having laterally spaced rollers, said receptacle having rails at the top of its side members arranged to run on said rollers and removably suspend the receptacle from and below its cover, and means for directing waste metal from the machine through the cover and into the receptacle.

3. A waste metal catcher for a type casting machine comprising a receptacle, a cover for the receptacle applicable to said machine in an elevated position and having laterally spaced depending side members, rollers journaled on said side members, said receptacle having rails at the top of its side members arranged to run on said rollers and removably suspend the receptacle from and below its cover, and means for direct-

ing waste metal from the machine through the cover and into the receptacle.

4. The combination with a type casting machine, of a waste metal catcher having a receptacle, a cover for the receptacle secured to said machine in an elevated position and extending substantially entirely outwardly thereof, said receptacle being removably suspended from and below its cover, and means for directing waste metal from the machine through the cover and into the receptacle.

5. The combination with a type casting machine having at one side thereof quadding and centering mechanism, of a waste metal catcher having a receptacle, a cover for the receptacle secured to said machine in an elevated position and extending substantially entirely outwardly of said machine and forwardly of the quadding and centering mechanism, and a receptacle being removably suspended from and below its cover, and means for directing waste metal from the machine through the cover and into the receptacle.

6. A waste metal catcher for a type casting machine having a waste metal spouting system, said catcher comprising a receptacle, a cover for the receptacle applicable to said machine in an elevated position, said receptacle being removably suspended from and below its cover, and a hopper on the cover constructed and arranged to receive waste metal from said system and direct the same through the cover and into the receptacle.

7. The structure defined in claim 6 which further includes an upstanding deflecting flange on the hopper for intercepting over-shot discarded slugs thrown by the operator of the machine and directing the same into the hopper.

8. A waste metal catcher for a type casting machine comprising a cover applicable to said machine in an elevated position and having depending side members, rollers journaled on said members, a receptacle having rails at the top of its side members arranged to run on said rollers and removably suspend the receptacle from and below the cover, and a hopper on the cover constructed and arranged to receive waste metal from said machine and direct the same through the cover and into the receptacle.

9. The combination with a type casting ma- 50

chine having a frame side member, quadding and centering mechanism, and a waste metal spouting system, of a waste metal catcher comprising a cover secured to said member in an elevated position and extending substantially entirely outwardly thereof and forwardly of the quadding and centering mechanism, a receptacle removably suspended from and below said cover, and a hopper on the cover and extending substantially entirely inwardly of said member, said hopper being constructed and arranged to receive waste metal from said spouting system and direct the same through the cover and into the receptacle.

10. The combination with a type casting machine having a vise frame leg pivoted thereto and also having the discharge spout of a type slug sawing attachment secured to said leg for common movement therewith, of a waste metal catcher having a support secured to said machine, a hopper on said support, and an apron hinged to the support, constructed and arranged to direct waste metal from said spout into the hopper and normally extending in the path of movement of said leg, said apron being actuated by the leg during movement thereof when the vise frame is being opened and moved out of its path of movement.

11. The structure defined in claim 10 in which the apron is returned to normal position under the action of gravity during movement of said leg while the vise frame is being closed.

12. The combination with a type casting machine having a vise frame leg pivoted thereto and also having the discharge spout of a type slug sawing attachment secured to said leg for common movement therewith, of a waste metal catcher having a support secured to said leg for common movement therewith, of a waste metal catcher having a support secured to said machine, a hopper on said support, and an apron hinged to the support, constructed and arranged to direct waste metal from said spout into the hopper and normally extending in the path of movement of said leg, said apron having a cam surface constructed and arranged to be engaged by said leg during movement thereof while the vise frame is opened and move the apron out of said path of movement.

GEORGE L. CURLE.
